(57) **CLAIM**

The ornamental design for a vehicle grille, as shown and described.

DESCRIPTION

FIG. 1 is a front perspective view of a vehicle grille in accordance with an embodiment of the present invention;

FIG. 2 is a front/left side perspective view of the vehicle grille of FIG. 1, wherein a front/right side perspective view is a mirror image thereof; and,

FIG. 3 is a left side perspective view of the vehicle grille of FIG. 1, wherein a right side perspective view is a mirror image thereof.

Then broken lines shown in the drawings form no part of the claimed design.
